Primary Examiner — Katherine A Holbrow(74) *Attorney, Agent, or Firm* — Alexandra S. Anoff(57) **CLAIM**

The design for a display screen with graphical user interface, as shown and described.

DESCRIPTION

The FIGURE is a front view of a display screen with graphical user interface, embodying the new design. Broken lines are used to illustrate portions of the display screen with graphical user interface or environmental subject matter that form no part of the claimed design. None of the broken lines form any part of the claimed design.
